DESIGN FOR A SIGNAL DEVICE

Lloyd Rittenhouse, Honeoye Falls, and Sidney M. Crossett, Rochester, N. Y., assignors to The A. E. Rittenhouse Co., Inc., Honeoye Falls, N. Y., a corporation of New York

Application July 20, 1938, Serial No. 78,604

Term of patent 3½ years

To all whom it may concern:

Be it known that we, Lloyd Rittenhouse and Sidney M. Crossett, both citizens of the United States of America, and residing at Honeoye Falls and Rochester, respectively, in the county of Monroe and State of New York, have invented a new, original, and ornamental Design for a Signal Device, of which the following is a specification, reference being had to the accompanying drawing, forming a part thereof.

In the drawing:

Fig. 1 is a view in front elevation of a signal device showing our new design, and

Fig. 2 is a top plan view of the same.

The characteristic features of the design reside in a signal device consisting of parts having the configuration, arrangement, and proportions, and on the shield or upper portion thereof the figure representation, as shown.

We claim:

The ornamental design for a signal device, as shown and described.

LLOYD RITTENHOUSE.
SIDNEY M. CROSSETT.
